(57) **CLAIM**

The ornamental design for a jugular tourniquet, as shown and described.

DESCRIPTION

FIG. 1 is a front perspective view of a jugular tourniquet taken from one perspective;

FIG. 2 is a front perspective view of a jugular tourniquet taken from the opposite of FIG. 1;

FIG. 3 is a front view thereof;

FIG. 4 is a top view thereof;

FIG. 5 is a bottom view thereof;

FIG. 6 is one-side view thereof; and,

FIG. 7 is a second side view thereof.

The portions of the jugular tourniquet shown in broken lines form no part of the claimed design.
